Attorney

UNITED STATES PATENT OFFICE.

ALEXANDER I. FERRIER, OF FLINT, MICHIGAN.

MECHANICAL MOVEMENT.

Application filed November 11, 1927. Serial No. 232,686.

This invention relates to mechanical movements and has special reference to a mechanical movement for transforming continuous rotary motion to oscillatory motion such as is used in windshield wipers, washing machines and the like.

One important object of the invention is to provide an improved device of this character having a special form of gear spacer 10 arranged to keep a rack and pinion in constant correct relationship.

A second important object of the invention is to provide an improved form of reciprocating element in such devices.

With the above and other objects in view as will be hereinafter apparent, the invention consists in general of certain novel details of construction and combinations of parts hereinafter fully described, illustrated 20 in the accompanying drawings and specifically claimed.

In the accompanying drawings like characters of reference indicate like parts in the several views, and:

25 Figure 1 is a horizontal section through the upper part of the casing enclosing the operating mechanism.

Figure 2 is a vertical section through the casing or housing and showing the operating 30 parts in position.

Figure 3 is a front view of the reciprocating element with the casing omitted.

In the construction of this invention there is provided a casing having a back wall 10 and top and bottom walls 11, the casing thus 35 forming a channel like structure and being indicated in general at 5. On the front of this casing a cover plate 6 is secured by screws 7. At the rear of the casing there is 40 provided a hub or bearing 12 through which extends a shaft 2 which projects within the casing and carries on its inner end a pinion 4. Between the pinion 4 and the wall 10 is a spacing disk 3. Within the casing is a reciprocating member 13 which is preferably 45 made of a die stamping and this member is of channel shape with the flanges 14 straddling the disk 3 and resting lightly against the rear wall 10. At the front end the 50 stamping is pressed to form ribs 15 adapted to bear against the cover plate 6, the friction between the reciprocating stamping and the casing being thus reduced to a minimum. Stamped out of this reciprocating 55 member is a rack 1 which meshes with the

pinion 4. At one end the member 13 is provided with a tongue 16 having an opening 17 therein for the reception of a crank pin the path of which may be considered to be the circle 18 in Figure 3. It will now be 60 seen that the disk 3, through its engagement with the flange 14, keeps the reciprocating element in proper position for the rack to mesh correctly with the pinion and that as the crank pin moves around the 65 path 18 the member 13 will have an oscillatory reciprocation which in turn will revolve the pinion 4 first in one direction and then in the other so that any element attached to the shaft 2 will oscillate.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come 80 within the scope claimed.

Having thus described the invention, what is claimed as new, is:

1. In a device of the kind described, a channel like casing, a cover plate therefor, a shaft extending into said casing, a pinion on said shaft, a second channel like member mounted in the casing for reciprocation therein, a spacing disk mounted on the shaft between the flanges of the second channel like member and guiding said member, and a rack carried by the second channel like member and engaging said pinion.

2. In a device of the kind described, a channel like casing, a cover plate therefor, a shaft extending into said casing, a pinion on said shaft, a second channel like member mounted in the casing for reciprocation therein, a spacing disk mounted on the shaft between the flanges of the second channel like member and guiding said member, and a rack carried by the second channel like member and engaging said pinion, the flanges of the second channel member engaging the back wall of the casing and said second channel like member having ribs extending longitudinally thereof to engage the cover plate.

In testimony whereof I affix my signature.

ALEXANDER I. FERRIER.
